US00D819632S

(12) **United States Design Patent** (10) **Patent No.:** **US D819,632 S**
(45) **Date of Patent:** **** Jun. 5, 2018**

(54) **VOICE RECOGNITION DEVICE**

(71) Applicant: **Quanta Computer Inc.**, Taoyuan (TW)

(72) Inventor: **Shih-Cheng Lin**, Taoyuan (TW)

(73) Assignee: **QUANTA COMPUTER INC.**,
Guishan Dist., Taoyuan (TW)

(**) Term: **15 Years**

(21) Appl. No.: **29/589,692**

(22) Filed: **Jan. 4, 2017**

(30) **Foreign Application Priority Data**

Dec. 1, 2016 (TW) 105307261

(51) **LOC (11) Cl.** **14-02**

(52) **U.S. Cl.**

USPC **D14/358**; D14/492; D14/167

Rodack, LLP

(57) **CLAIM**

The design for voice recognition device, is as shown and
described.

DESCRIPTION

FIG. 1 is a front perspective view of a voice recognition
device showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a rear perspective view thereof.

1 Claim, 8 Drawing Sheets
